UNITED STATES PATENT OFFICE.

CHARLES Z. ELLIS, OF BERKELEY, CALIFORNIA, ASSIGNOR OF ONE-HALF
TO ROBERT C. LANE, OF BERKELEY, CALIFORNIA.

FEED-REGULATOR FOR ORE-FEEDERS.

SPECIFICATION forming part of Letters Patent No. 745,169, dated November 24, 1903.

Application filed April 23, 1902. Serial No. 104,280. (No model.)

To all whom it may concern:

Be it known that I, CHARLES Z. ELLIS, a citizen of the United States, and a resident of Berkeley, in the county of Alameda and State 5 of California, have invented a new and Improved Feed-Regulator for Ore-Feeders, of which the following is a full, clear, and exact description.

This invention relates to improvements in machines for feeding ore to quartz-crushers or similar devices; and the object is to provide an ore-feeder of simple construction and by means of which the ore can be evenly fed to the crusher or the like.

15 I will describe an ore-feeder embodying my invention and then point out the novel features in the appended claims.

Reference is to be had to the accompanying drawings, forming a part of this specification, 20 in which similar characters of reference indicate corresponding parts in all the figures.

Figure 1 is a side elevation of an ore-feeder embodying my invention. Fig. 2 is a rear elevation thereof. Fig. 3 is a plan view. Fig. 25 4 is a detail showing means for operating the feeding-cylinder, and Fig. 5 is a sectional detail showing the feed-regulator.

The ore-feeder comprises a cylinder 1, mounted on a shaft 2, which has its bearings 30 in the upper portion of a frame 3. This cylinder is provided at its ends with outwardly-extended annular flanges 4, and outward of these flanges are cylindrical ledges 5. Mounted to rock on the shaft 2 at opposite ends of 35 the cylinder are levers 6, which are connected at the front and provided with a handle 7. On the rear ends of the levers 6 are adjustably arranged balancing-weights 8. Each lever is provided with a block 9, which extends across the cylindrical ledge 5, and the 40 inner and outer walls or sides of this block are inclined upward and outward, so that the upper portion of the block is at a greater distance from the cylindrical ledge 5 than is the lower portion, and placed between the blocks 45 9 and the portions 5 of the cylinder are bearing-balls 10. These levers 6 are designed to impart a step-by-step rotation to the cylinder—that is, by moving the handle 7 up and 50 down the downward movement of said handle

will cause of course the rearward portions of the levers to move upward—and during this motion the balls 10 will crowd in between the blocks 9 and the cylinder and by friction cause the cylinder to rotate as described. Upon a 55 reverse movement the wider portion of the space between the blocks 9 and the cylinder will receive the balls, and thus relieve the frictional engagement and prevent a reverse rotary movement of the cylinder. The set-screw 60 6^a, attached to the rear part of the frame, regulates the space through which the handle or lever travels, thus regulating the rotary movement of the cylinder. As the balls are of varying diameters, they will all bear upon the cylinder, and thus provide a comparatively large 65 friction-surface.

Arranged above the cylinder is a hopper 11, the rear wall of which is inclined, as shown, and the bottom of the front wall is provided 70 with an opening 12, which is controlled by a gate-valve 13. This gate-valve slides against the inner side of the front wall of the hopper and is held as adjusted by means of bolts 12^a, passing from the valve through slots in said 75 front wall. The side walls of the hopper are conformed to the shape of the cylinder and rest thereon. Attached to the hopper are standards 14, the lower ends of which are forked to engage upon the shaft 2, so that the 80 hopper may be rocked back and forth or adjusted. The adjustments are made by means of a screw 15, operating in a nut 16, attached to the machine-frame and having a pivotal or swinging connection 17 at the upper end with 85 the rear wall of the hopper. The front wall is so inclined that as the hopper is carried forward of the vertical center of the cylinder it will approach the perpendicular.

The material falling from the cylinder 90 passes into a chute 18, and from this chute it falls into a crusher or other machine. The chute has an adjustable attachment to the frame, and the upper end of the chute coming in contact with the cylinder acts as a scraper. 95

The rotation of the cylinder is for the purpose of causing a disturbance between and a separation of the particles or pieces of matter contained in the hopper, at the same time carrying the matter forward toward the gate 100

or outlet of the hopper. The hopper is made adjustable for the purpose of regulating the feed from the hopper, and the sliding gate of the hopper is also made adjustable for the same purpose. As the hopper is carried rearward of the vertical center of the cylinder the effective component of gravity becomes inoperative, thus decreasing the quantity of matter finding its escape through the gate of the hopper. When the hopper is carried forward of the vertical center, the feeding component of gravity becomes more operative, hence causing an increase of the amount of matter passing through the outlet. The hopper being patterned so, its front wall approaches the perpendicular as the hopper is carried forward for the purpose of further increasing the effect of gravity. This is necessary if the matter being fed is adhesive, as it is if it be wet, full of clay or other sticky matter, which is often the case. Dry matter will be prevented from falling directly into the chute by the sliding gate of the hopper and by carrying the hopper rearward and by decreasing the rotary motion of the cylinder. Hence with the sliding gate, oscillating hopper, and speed regulating of the cylinder we have an accurate adjustment of the amount of matter fed, whether it be dry or wet, coarse or fine, adhesive or not.

Having thus described my invention, I

claim as new and desire to secure by Letters Patent—

1. In an ore-feeder, a frame, a cylinder mounted to rotate in the frame, annular flanges at the ends of the cylinder, cylindrical ledges at the outer sides of the flanges, levers mounted to rock at opposite ends of the cylinder, blocks carried by the levers and extended across the cylindrical ledges, the sides of the blocks adjacent to the ledges being inclined upward and outward, a series of bearing-balls arranged between the blocks and ledges, the said balls being of varying diameters, and a hopper arranged above the cylinder, substantially as specified.

2. In an ore-feeder, a frame, a cylinder mounted to rotate in the frame, levers mounted to rock at opposite ends of the cylinder, blocks carried by the levers and divergent from the cylinder from the lower end upward, a series of bearing-balls arranged between the blocks and cylinder, the said balls being of varying sizes, and a hopper over the cylinder, substantially as specified.

In testimony whereof I have signed my name to this specification in the presence of two subscribing witnesses.

CHARLES Z. ELLIS.
